UNITED STATES PATENT OFFICE.

ELI T. FORRESTER, OF WASHINGTON, DISTRICT OF COLUMBIA.

RAILWAY-TIE.

No. 853,629.

Specification of Letters Patent.

Patented May 14, 1907.

Application filed March 21, 1907. Serial No. 363,693.

To all whom it may concern:

Be it known that I, ELI TAYLOR FORRESTER, a citizen of the United States, residing at Washington, in the District of Columbia, have invented a new and useful Railway-Tie, of which the following is a specification.

This invention relates to rail ties and fasteners and is more particularly an improvement upon the tie described and claimed by me in United States Patent No. 810,200, dated January 16, 1906.

The object of the invention is to improve the construction of the tie whereby the fastener securing means can be readily detached without the necessity of removing ballast from beneath the tie.

A still further object is to improve fasteners of novel form designed to be grouped in pairs upon the tie for engaging a rail at opposite sides thereof, said fasteners, being shaped to accommodate themselves to curved as well as straight rails.

Another object is to provide a fastener capable of engaging and holding a rail when adjusted to various positions without the necessity of shifting the fasteners longitudinally upon the tie.

With these and other objects in view the invention consists of certain novel features of construction and combinations of parts which will be hereinafter more fully described and pointed out in the claims.

In the accompanying drawings is shown the preferred form of the invention.

In said drawings: Figure 1 is a perspective view showing the tie in position with rails secured thereon; Fig. 2 is a plan view of one end portion of the tie and showing a rail thereon; Fig. 3 is a perspective view of one end portion of the top plate of the tie, the same being shown inverted; and Fig. 4 is a transverse section through the tie and fasteners.

Referring to the figures by characters of reference, 1 designates a series of superposed metallic strips and between every two of these strips is arranged a layer of cushioning material 2. These layers are preferably formed of a fibrous material such as wood pulp or paper pulp, molded into proper shape. A cushioning layer 3 similar to the layer 2 is also arranged upon the upper strip 1 and extending throughout the length of this layer and bearing thereon is a top plate 4 which is preferably considerably heavier than the metallic strips 1. This plate is fastened to the cushioning layers and to the strips 1 in any

desired manner as by means of rivets 5 extending entirely through them at desired intervals. It is to be understood of course that the parts are pressed tightly together so as to form a solid tie body.

Extending laterally from the top plate near the ends thereof are side extensions 6 which are thicker than the top plate and lap the upper cushioning layer 3 as shown particularly in Fig. 4. Each of these side extensions has angular openings 7 extending therethrough, each extension being preferably formed with two openings.

The upper face of each extension has an angular recess 8 surrounding the upper end of each of the openings 7 and each recess is designed to receive an angular boss 9 formed upon the lower face of a fastening member 10. This member has an opening therethrough to receive a securing bolt 11 which is insertable into one of the openings 7 from the lower end thereof and is designed to be secured within the fastener by means of a nut 12, there being a spring member 13 serving to lock the nut against displacement.

The body of the fastener 10 is substantially rectangular and has wings 14 extending from the sides thereof. These wings are disposed preferably at right angles to each other and have their lower faces inclined so as to fit snugly upon the base flange of a rail 15. The wings 14 are of different lengths and by loosening the bolt 11 of the fastener boss 9 can be lifted from the recess 8 and the fastener turned so as to bring any one of the wings in position upon the base flange of the rail. It is of course apparent that when the fastener is secured in place with its boss in the recess 8 it becomes impossible for said fastener to turn out of adjusted position.

An important feature of the present invention resides in the fact that the fasteners are secured upon side extensions 6 formed with the top plate of the tie. As a result of this construction, the tie can be placed within a road bed and should it be desired to remove one of the bolts 11 should the same become broken, it is merely necessary to remove a portion of the ballast from under the extension 6. Where the fastening means extends entirely through the tie it is of course necessary to remove the ballast from beneath the tie as well as from the sides thereof in order to remove said means.

Another feature to which importance is attached is the provision of side extensions

which lap the upper cushioning layer of the tie at the points where the greatest pressure is received, thereby preventing said cushioning means from spreading out of position.

5 It will also be noted that the fastening devices are arranged in pairs, one pair being located on each of the side extensions so as to engage a rail at points directly opposite each other. There is therefore no danger of the 10 rails springing away from any of the fasteners and thus gradually working loose.

The tie herein shown and described is one of those to be ordinarily used by me. It is to be understood, however, that the relative positions, shapes and sizes of the side extensions 15 can be varied and the shape and size of the tie body can be changed where the tie is to be used at switches, crossings, etc.

What is claimed is:

20 1. A railway tie made up of a series of alternating metallic and fibrous layers, a top plate, side extensions integral with said plate and lapping one of the fibrous layers, and binding elements piercing the top plate and the layers of the tie.

2. A railway tie comprising a top plate having integral side extensions, and alternating metallic and fibrous layers disposed below the top plate, one of said layers being lapped by the side extensions.

3. A railway tie comprising cushioning means, a top plate secured thereon and having integral side extensions, and fastening means mounted upon the extensions.

4. A railway tie comprising cushioning means, a top plate secured thereon and having side extensions, said extensions constituting retainers for the cushioning means, rail fasteners upon each of said extensions, and means insertible through the extensions from 35 the bottoms thereof for securing the fasteners upon the extensions.

In testimony that I claim the foregoing as my own, I have hereto affixed my signature in the presence of two witnesses.

ELI T. FORRESTER.
